RAZOR BLADE GRINDING MACHINE

Werner Tobias, Berlin-Sudende, Germany, assignor to Aktiebolaget Tensor, Gottenburg, Sweden

Application November 26, 1932, Serial No. 644,471
In Germany December 4, 1931

2 Claims. (Cl. 51—74)

This invention relates to grinding machines and more particularly, although not exclusively, to grinding machines in which each of several grinding discs has to carry out a definite grinding operation on a piece of work, e. g. the grinding of the cutting edges on a continuous progressed steel band from which thin razor blades are made. These grinding discs have to be brought out of engagement with the piece of work during interruptions in working, start without load on continuation of the grinding operation and then be first again brought near to the piece of work and finally be brought into contact with the work. The retraction and re-adjustment of the discs to the exact extent of grinding may be brought about by arranging the slide supporting the spindle of the grinding disc to be urged by a spring in the work-engaging direction so that on the retraction of the grinding disc it is only necessary to compress the spring. In this case no change need be made to the abutment which is capable of regulation by fine adjustment for the exact positioning of the slide in the work-engaging position so that on repositioning to the work the disc can be brought exactly into the original working position. The invention provided an arrangement for the retraction and return to the working position of the slide which carries the grinding disc, which consists of a guide for an adjusting nut, a cam roller arranged on the support slide and a cam mounted on a shaft in the machine frame. The cam has a shape such that it gives, in its retracted position, sufficient play to allow of wear of the grinding disc. The retracting devices of several grinding discs which operate on the same piece of work may be connected by a rod in such a manner that engagement with the work and disengagement may be brought about in common from one position.

In order that the invention may be clearly understood and readily carried into effect, it will now be explained more fully with reference to the accompanying drawing in which:—

Fig. 1 illustrates in section an example of a grinding apparatus according to the invention,

Fig. 2 is a section through Fig. 1 according to the lines 2—2,

Fig. 3 is a side view of a part of Fig. 1 shown from the left-hand side,

Fig. 4 is a plan of a part of Fig. 1 and

Fig. 5 is a perspective view of the guiding means for the steel band and

Fig. 6 is a front view of a plurality of grinding apparatus according to the invention as ar-

ranged as to be commonly engaged and disengaged.

a is the grinding disc, which is carried with its bearing bushing *b* in the slide *c* can be moved up and down with it in the machine pedestal *d* in the direction of the arrow *e*. For the purpose of guiding the slide *c* within the pedestal *d* the slide is provided with ribs *c*¹ engaging a groove formed between the edges of the pedestal *d* and guiding ledges *d*¹ fastened on the pedestal by means of screws or the like (see Fig. 2). *f* is the work, which moves perpendicularly to the plane of the drawing between the guides *g* and *h* and in this case is ground on the edge *i*. It is here a case, for example, of a continuously moved steel band, on both sides of which cutting edges are ground, whereupon the steel band is divided into individual thin razor blades. The guide *h* is a fixed part of the machine while the guide *g* is yieldingly held against the guide *h* by means of screws *g*¹ passing through holes within the guide *g* and being screwed into the guide *h*, springs *g*² being interposed between the heads of the screws and the guides *g*. The steel band is fed to and delivered from said guides *h* and *g* by means of rollers *h*¹ (Fig. 5).

The grinding disc *a* is held in the position shown in Fig. 1 in which it engages the work piece *f* by coming into contact of the support *c* with the abutment surface *k* of the nut *m* under the pressure of the spring *l*. The nut *m* is guided in a cylindrical part *w* forming a portion of the pedestal and is secured against rotation by a guide *n* facing a flattened portion of said nut and held within the cylinder *w* by means of a screw *n*¹. The nut *m* engages the threaded part *o* of a spindle *o*¹ journalled on the one side in the bottom of the cylindrical part *w* and on the other side within a cap *d*² fastened for instance by means of screws on the pedestal *d*. The spring *l* is laid around the said spindle *o*¹ and abuts against two discs *y*¹ and *y*² respectively, engaging the pedestal *d* and the slide *c* respectively.

For the purpose of adjusting the position of the grinding disc *a* the spindle *o* may be turned by means of a worm wheel *p* fastened on the upper end of the spindle *o*¹ and engaging a worm *q* which may be turned in any desired manner. For the purpose of retraction out of the working position, the support slide *c* is provided with a roller *r*, and a cam *t* is rotatably mounted on a shaft *s* in the machine pedestal *d* so formed that in the position illustrated in Figs. 1 and 2 it has sufficient play towards the roller *r* to allow of advance of the grinding disc, if its diameter is

reduced as a result of wear during working. The cam *t* can be turned by means of the lever *u*, mounted on the shaft *s* and the connecting rod *v*, to such an extent that it raises the roller *r* and with it the grinding disc *a* against the action of the spring *t* and thus brings the grinding disc *a* out of engagement with the work *f*.

Figs. 1 to 5 of the drawing shows only one grinding disc but of course several grinding discs could be employed at the same time for operating on the work at its various working surfaces as shown in Fig. 6. The rod *v* may then engage simultaneously with the cam levers of the other grinding machines provided for operating on the work, so that their engagement and disengagement can be brought about simultaneously.

The grinding disc may be rotated by any suitable means. In Fig. 6 of the drawing the spindle *a*¹ of the wheel is provided with a pulley *z* which may be driven.

I claim:—

1. A grinding machine for grinding cutting edges on a continuously progressing steel band, comprising means to continuously feed the steel band, guides to hold and support the portion of the steel band to be momentarily worked, a grinding disc arranged opposite said guides, a slide carrying the disc, a pedestal in which the said slide is displaceable in a direction perpendicular to the disc axis, a spring arranged in the pedestal

and adapted to urge the slide in a direction to engage the portion of the work guided between said guides, an adjustable abutment adapted to determine the working end position of the slide, and manually actuated means for disengaging the disc from the work counteracting to the said spring and comprising a cam roller and a cam arranged on the slide and the pedestal of the machine, respectively, and co-operating with each other but being out of contact during the working of the disc.

2. A grinding machine for grinding cutting edges on a continuously progressing steel band, comprising means to continuously feed the steel band, guides to hold and support the portion of the steel band to be momentarily worked, a grinding disc arranged opposite said guides, a slide carrying the disc, a pedestal in which the said slide is displaceable in a direction perpendicular to the disc axis, a spring arranged in the pedestal and adapted to urge the slide in a direction to engage the portion of the work guided between said guides, and manually actuated means for disengaging the disc from the work counteracting to the said spring and comprising a cam roller and a cam arranged on the slide and the pedestal of the machine, respectively, and co-operating with each other but being out of contact during the working of the disc.

WERNER TOBIAS. 30
